UNITED STATES PATENT OFFICE.

MILTIADES ATH. BECOLAS, OF ST. LOUIS, MISSOURI.

DESIGN FOR A CONDIMENT-HOLDER.

55,360.

Specification for Design.

Patented June 1, 1920.

Application filed September 19, 1919. Serial No. 325,021. Term of patent 3½ years.

To all whom it may concern:

Be it known that I, MILTIADES A. BECOLAS, a subject of the King of Greece, residing at St. Louis, and State of Missouri, have invented a new, original, and ornamental Design for a Condiment-Holder, of which the following is a specification, reference being had to the accompanying drawing, forming a part thereof.

The figure is a perspective view of the condiment holder showing my new design.

I claim:

The ornamental design for a condiment holder as shown.

MILT. ATH. BECOLAS.
